US00D656321S

(12) **United States Design Patent**
Thompson et al.

(10) **Patent No.:** US D656,321 S
(45) **Date of Patent:** ** Mar. 27, 2012

(54) **SHEET MATERIAL**

(75) Inventors: **Michelle Christine Thompson**,
Montgomery, OH (US); **Jamey Nathan
Wagner**, West Chester, OH (US);
Brandy Nicole Lockaby, Cincinnati,
OH (US)

(73) Assignee: **The Procter & Gamble Company**,
Cincinnati, OH (US)

(**) Term: **14 Years**

(21) Appl. No.: **29/404,825**

(22) Filed: **Oct. 26, 2011**

(51) **LOC (9) Cl.** 05-05

(52) **U.S. Cl.** D5/37

(58) **Field of Classification Search** D5/6, 16,
D5/26, 32, 36, 37, 53, 55, 57, 59, 62, 63,
D5/66, 99; D6/582, 588, 600, 609, 614,

(57) **CLAIM**

The ornamental design for a sheet material, as shown and described.

DESCRIPTION

The sole FIGURE is a top plan view of a sheet material showing our new design. The broken lines shown outside the border of the figure indicate that a specific length and width of the sheet material forms no part of the claimed design. The broken lines in the drawing represent environmental subject matter that forms no part of the claim.

1 Claim, 1 Drawing Sheet
